UNITED STATES PATENT OFFICE

LESTER GEORGE SARGENT, OF KEENE, NEW HAMPSHIRE

DESIGN FOR A GOLF TEE

Application filed January 16, 1930. Serial No. 34,152. Term of patent 14 years.

To all whom it may concern:

Be it known that I, LESTER G. SARGENT, a citizen of the United States, residing at Keene, in the county of Cheshire and State of New Hampshire, have invented a new, original, and ornamental Design for Golf Tees, of which the following is a specification, reference being had to the accompanying drawing, forming part thereof.

Fig. 2 is a perspective view of same.

I claim:

The ornamental design for a golf tee, as shown.

LESTER GEORGE SARGENT.
